(57) **CLAIM**

The ornamental design for a T-shirt, as shown and described.

DESCRIPTION

“The patent or application file contains at least one drawing executed in color. Copies of this patent with color drawing(s) will be provided by the Patent and Trademark Office upon request and payment of necessary fee.”

FIG. 1 is a front view of a T-shirt showing my new design;

FIG. 2 is a rear view thereof;

FIG. 3 is a left side view thereof;

FIG. 4 is a top view thereof;

FIG. 5 is a bottom view thereof;

FIG. 6 is an enlarged view of the image shown in sections B and D of FIG. 1;

FIG. 7 is an enlarged view of the image shown in sections E and F of FIG. 2;

FIG. 8 is an enlarged view of the image shown in sections A and C of FIG. 1; and,

FIG. 9 is an enlarged view of the image shown in sections A' and C' of FIG. 1;

The broken lines on the outer edges of FIGS. 6–9 represent an unclaimed boundary.
